UNITED STATES PATENT OFFICE

123,152

DESIGN FOR A TOWEL OR SIMILAR ARTICLE

Vera Way Marghab, New York, N. Y.

Application August 1, 1940, Serial No. 94,110

Term of patent 14 years

To all whom it may concern:

Be it known that I, Vera Way Marghab, a citizen of the United States, residing at New York, county and State of New York, have invented a new, original, and ornamental Design for a Towel or Similar Article, of which the following is a specification, reference being had to the accompanying drawings, forming part thereof, wherein—

Fig. 1 is a plan view of a towel or similar article showing my new design.

Fig. 2 is an enlarged detail view of the design shown in Fig. 1.

I claim:

The ornamental design for a towel or similar article, substantially as shown and described.

VERA WAY MARGHAB.
